UNITED STATES PATENT OFFICE.

EDWARD G. DAVIS, OF PARIS CROSSING, INDIANA.

FUSE.

1,128,764.

Specification of Letters Patent. Patented Feb. 16, 1915.

Application filed May 4, 1914. Serial No. 836,264.

To all whom it may concern:

Be it known that I, EDWARD G. DAVIS, a citizen of the United States, residing at Paris Crossing, in the county of Jennings 5 and State of Indiana, have invented certain new and useful Improvements in Fuses, of which the following is a specification.

An object of this invention is the provision of a fuse including a fusible conductor and means for detachably securing and inclosing said conductor.

Another object of the invention is the provision of a fuse including a casing and caps detachably secured over the ends thereof 15 carrying spring contacts having frictional contact with the fusible conductor.

With these and other objects in view, the invention consists in the novel construction, arrangement and combination of parts as 20 will be hereinafter specifically described, claimed and illustrated in the accompanying drawings, in which,

Figure 1 represents a side elevation of the improved fuse, partly in section, Fig. 2 25 represents a front elevation thereof, partly in section; and, Fig. 3 represents a transverse sectional view on the line 3-3 of Fig. 1.

Referring to the drawing in detail, where- 30 in similar reference numerals designate cor- responding parts throughout the several views, the numeral 1 indicates a cylindrical casing having both ends open and preferably formed of a suitable insulating com- 35 position. Annular members 2 having in- wardly directed flanges 3 are frictionally engaged over the ends of the casing 1 and are formed with diametrically elongated openings 4 receiving the ends of the fusible 40 conducting wire 5, which are bent over the inwardly directed flanges 3 at right angles to the elongated openings 4, as indicated at 6. A suitable filling of asbestos or similar material is positioned within the casing 1 45 and completely insulates the latter from the conductor 5.

The sleeve or annular member 2 is pro-

vided with a pair of diametrically opposed and outwardly directed pins 8 adapted to coöperate with the arms 9 of the clip 10 having pivotal connection at 11 with the caps 12 having closed ends 13 carrying suitable terminals 14. The end wall 13 of the cap 12 is normally spaced a distance from the inwardly directed flange 3 and is 50 formed of a suitable conducting material such as copper. A pair of U-shaped springs 15 having their free ends 16 overlapped are secured to the inner face of the end wall 13 and frictionally engage the turned end 6 55 of the conducting wire 5 to provide an electrical connection between the terminals 14 at the opposite ends of the fuse.

When it is desired to replace or reload the fuse, the clips 10 are swung outwardly 60 on their pivots 11 and the caps 12 removed from the fuse casing 1. The annular mem- bers 2 are subsequently turned to align the angularly directed ends 6 of the wire 5 with the diametrically elongated openings 4, and 65 removed. The fusible wire 5 and filling 7 are then removed and the new fuse wire and filling are replaced in the casing 1.

What I claim is:—

A device of the character described com- 70 prising a casing, annular members rotatably mounted on the ends of said casing and having diametrically elongated openings there- 75 in, a fusible member positioned within said casing, extending through the openings in 80 said annular member and having the oppo- site ends bent over said annular members at right angles to the elongated openings of the latter, caps detachably secured to said annular members, and oppositely arranged 85 U-shaped spring contacts in said casing nor- mally engaging the bent ends of said fusi- ble member.

In testimony whereof I affix my signature in presence of two witnesses.

EDWARD G. DAVIS.
